UNITED STATES PATENT OFFICE.

WILLIAM W. FORD, OF PHILADELPHIA, PENNSYLVANIA.

TANK STRUCTURE AND LUG THEREFOR.

Application filed June 24, 1924. Serial No. 722,024.

To all whom it may concern:

Be it known that I, WILLIAM W. FORD, a citizen of the United States, residing at Philadelphia, in the county of Philadelphia and State of Pennsylvania, have invented new and useful Improvements in a Tank Structure and Lug Therefor, as set forth in the annexed specification.

My invention relates to new and useful improvements in a tank structure and lug therefor, and has for its primary object to provide means of different characters all acting to strengthen the tank structure.

Another object of the invention is to provide a sister tank lug as a connection for the ends of the hoop whereby a straight double pull may be exerted on said hoop to facilitate the tightening thereof and assist in properly maintaining the hoop in position.

A further object of this invention is to provide a tank lug of open or skeleton construction whereby the majority of the threads on the ends of the hoop or those portions of the hoop ends lying in the lug may be painted to protect the same against atmospheric conditions as well as to protect it against attacks by acid or gases which may be floating in the surrounding atmosphere thereby greatly increasing the life of the hoops.

With these ends in view, this invention consists in the details of construction and combination of elements hereinafter set forth and then specifically designated by the claims.

In order that those skilled in the art to which this invention appertains, may understand how to make and use the same, I will describe its construction in detail, referring by numerals to the accompanying drawings forming a part of this application, in which:—

Fig. 1, is a fragmentary sectional side elevation of a tank having my improvements applied thereto.

Fig. 2, is an enlarged plan view of one of the tank rafter brackets.

Fig. 3, is a section at the line 3—3 of Fig. 2.

Fig. 4, is a perspective view of the same.

Fig. 5, is an enlarged plan view of one of the tank lugs.

Fig. 6, is a side elevation thereof.

Fig. 7, is an end view of the same.

Fig. 8, is a section at the line 8—8 of Fig. 5.

In carrying out my invention as here embodied, 2 represents a tank of any usual or well known construction such as are used for storing water and the like in large quantities on tops or buildings and towers. The walls of such a tank are held together, supported or braced by a number of hoops 3 formed from metal rods and having their ends threaded as at 4 to receive the nuts 5.

In order to fasten the ends of a hoop in place and permit tightening of the same with a straight pull in opposite directions, I provide a tank lug 6 the structural details of which are illustrated in Figs. 5 to 8 inclusive.

This tank lug is of "sister" construction including a body 7 the inner surface of which is arcuate longitudinally as indicated at 8 so as to approximately correspond to the curvature of the tank walls. At each end of the body but offset relative to each other is a bearing surface 9 having an opening 10 therethrough for the passage of an end of a hoop. In alignment with each opening 10 but at the opposite end of the body is a recess 11 in which the hoop is seated so that one of these recesses is directly beside each bearing surface.

Intermediate each bearing surface and its associated recess the body is apertured as indicated at 12 thereby providing two side walls 13 and an intermediate partition 14.

After the hoop has been placed about the tank one end is inserted in a recess 11 and then passed through the opening 10 in endwise alignment therewith while the opposite end of the hoop is inserted in the other recess 11 and passed through the other opening 10. Next the nuts 5 are screwed on the threaded projecting ends of the hoop until they engage the bearing surfaces 9 after which the screwing of the nuts on the ends of the hoop will draw the latter taut from two opposite directions so that a greater and more even stress can be placed on the hoop than is possible with lugs of present day construction.

As this tank lug is of the "sister" construction the pull remains straight at all times and the hoop is prevented from buckling since any tendency of the strain on the hoop to twist or turn the lug in one direction is counteracted by a

similar action in the opposite direction and on the opposite end of the lug.

The open work or skeleton formation of the lug due to the apertures 12 gives access 5 to the portions of the hoop ends within the confines of the lug as well as the inner surfaces of said lug so that said hoop ends and the surfaces of the lug may be painted or otherwise coated with a suitable substance to 10 protect the same against damage due to conditions of the atmosphere or impairment of the elements.

In order to strengthen the upper edge of the tank and also provide means for holding 15 the rafters of the tank top, I provide a tank rafter bracket 15 the construction of which is shown in detail in Figs. 2 to 4 inclusive, wherein the numeral 16 denotes a stirrup comprising a bottom wall 17, an end wall 20 18 and a pair of spaced side walls 19, the latter having holes 20 therethrough. From the bottom wall 17 of the stirrup projects a trunnion 21 which passes through a hole 22 in the step 23 of the hanger 24. Said 25 hanger in addition to the step 23 includes a riser 25 from the upper end of which projects a plate 26 adapted to overlie the upper edge of the tank wall, the latter preferably being notched to receive the plate 26 so that 30 the upper surface of said plate will lie flush with the extreme top edge of the tank wall. At the outer end of the plate is formed a depending flange 27 adapted to engage the outer surface of the tank wall.

35 As will be readily noted the construction of this rafter bracket is such that when placed on the edge of a tank wall it requires no fastening means to hold it in position. Any desirable number of these brackets may 40 be used, the same being placed in alignment on opposite sides of the tank so that the ends of a rafter 28 may be set in the stirrups, these being swung to any angle on their respective hangers to compensate for the curvature of the tank, and when a rafter is in place bolts 29 are inserted in the holes 20 and passed through the ends of said rafter which will prevent any tendency of the tank

walls to bulge or flare outward. These bolts are held in place by nuts 30 screwed on their 50 threaded ends.

The stirrup is held on the hanger by a cotter pin 31, or its equivalent, passing through the trunnion 21 beneath the stop 23.

After the desired number of rafters are 55 in place the tank top 32 is laid thereon with its edges projecting over or on to the upper edge of the tank. Generally in tanks of this character a peaked cover is placed thereon to shed rain water or otherwise protect 60 the tank against damage by the elements.

Of course I do not wish to be limited to the exact details of construction as herein shown as these may be varied within the limits of the appended claims without departing from the spirit of my invention.

Having thus fully described my invention, what I claim as new and useful is:—

1. A structure comprising, in combination, a tank, hoops surrounding said tank and having threaded meeting ends, a sister lug for each hoop into which the threaded ends are inserted, nuts screwed on said threaded ends and engaging opposite ends of the sister lug, brackets including hangers 70 to engage the upper edge of the tank, stirrups adjustably mounted on the hangers and positioned within the tank, a rafter having its ends seated in the stirrups, and means to fasten the ends of the rafter in the stirrups. 75

2. A tank lug comprising a body having an arcuate face for coaction with a tank, a bearing surface with an opening therethrough at opposite ends of the body and out of alignment with each other, said body 85 further having recesses in alignment with the opening in each bearing surface and at the end of the body opposite the bearing surface with whose opening it is in alignment and said body further having apertures between the bearing surfaces and their respective recesses to permit easy access to the interior of the lug.

In testimony whereof, I have hereunto affixed my signature.

WILLIAM W. FORD.
